UNITED STATES PATENT OFFICE.

WILLIS H. SANBURN, OF SPRINGFIELD, MASSACHUSETTS, ASSIGNOR TO STRATHMORE PAPER COMPANY, OF MITTINEAGUE, MASSACHUSETTS, A CORPORATION OF MASSACHUSETTS.

MANUFACTURE OF PAPER.

1,191,912.

Specification of Letters Patent. Patented July 18, 1916.

Application filed May 5, 1915. Serial No. 26,177.

To all whom it may concern:

Be it known that I, WILLIS H. SANBURN, a citizen of the United States of America, and resident of Springfield, in the county of

5 Hampden and State of Massachusetts, have invented certain new and useful Improvements in the Manufacture of Paper, of which the following is a full, clear, and exact description.

10 This invention relates to ways and means for producing a paper which possesses a characteristic appearance in that it has areas, lines or superficial portions in contrast with other areas, lines, or superficial portions thereof,—the production being one which has an extensive adaptability for use as cover papers and for other purposes, and for which considerable demand and ready acceptability in the trade has been shown.

15 In carrying out the invention for the production of paper having a surface made up of contrasting portions, a coloring matter or material to contrast with the sheet or web is applied to the surface of a moist pulp sheet or web, and such sheet or web, while moist, with the color thereon is subjected to pressure to cause the color to spread irregularly on the surface of the paper.

20 As the invention is perhaps the more extensively carried out, a sheet or web of paper, having relatively thick and thin areas or portions therein has coloring matter or equivalent material for affecting its aspect applied on the surface thereof, which material is 35 then displaced from the high or prominent surface portions to places of occupancy in the depressions at the thinner portions of the web or sheet.

The invention is described in conjunction 40 with the accompanying drawings and is defined in the claims.

In the drawings: Figure 1 is a sectional elevation showing a portion of the "wet end" of a Fourdrinier paper machine which 45 comprises a means for the carrying out of the invention. Fig. 2 is a plan view of the same, on a somewhat reduced scale, while Fig. 3 is an elevation as seen looking forwardly beyond the plane indicated by line 50 3—3, Fig. 1. Figs. 4, 5, 6, 7 and 8 are face and sectional views illustrating the paper produced by the exercise of this invention. Figs. 9, 10, 11 and 12 are views illustrating modifications of devices and arrangements

specifically different from those represented 55 in Figs. 1, 2 and 3 but to be regarded as available for use within the purview of the invention.

First referring to the drawing, Figs. 1, 2 and 3 representing the equipment of a Fourdrinier paper machine in a manner which is regarded as most practical and desirable for the carrying out of the objects of this invention. A represents a gauze screen or apron, generally termed the "wire," B and C 60 the upper and lower couch rolls around the lower one of which the wire runs, and the upper one having the enveloping covering or jacket a of felt as usual. D represents the dandy roll. Forward of the dandy roll, 65 between the latter and the upper couch roll, and in proximity to such roll is a tank E which is suitably supported above the top of the wire and which extends horizontally and transversely of the paper machine. 70 This tank is for receiving and containing at a uniform level therein the liquid coloring matter or equivalent material which is employed for affecting the aspect of the paper. The color is maintained in the tank E up to 75 the desired height from a pipe b which leads thereto from a service tank F, to which the color from a reservoir is furnished by way of pipe d automatically controlled by ball cock e. G represents a cylindrical 80 brush ranging lengthwise of the color tank and to be partially submerged therein, such brush being sustained on suitable supports or brackets and is positively driven at a desired rate of speed, f representing a pulley on its arbor and f² a belt running therearound and which is understood as driven in any suitable manner, as, for instance, from any pulley-provided shaft of the paper machine. H represents a blade 85 which is carried on a bar J which is arranged above and parallel with the axis of the brush and has end journals or trunnions g to afford rocking supports for the blade-carrying bar, such journals or trunnions being mounted in bearing supports of the end brackets in which the arbor of the brush is mounted. The blade H is to be so swung, as one with its carrying bar J, and adjusted as to have an impingement against the 90 radial bristles of the cylindrical brush so that under the revolution of the latter, they by their impingement against the blade be-

- come retarded or rearwardly deflected, and thereafter on liberation from their engagement with the blade have forwardly accelerated springing movements for acquiring a 5 spraying effect of the color, brought around by the brush from the tank, onto the surface of the upper couch roll. One end journal of the oscillatory bar J on which the blade H is mounted is provided with a lever handle h by which the swinging adjustment of the bar for the most desirable positioning of the blade in relation to the brush is acquired; and in order that the blade-carrying bar when satisfactorily adjusted may be 10 so confined, one of the supporting brackets in which the adjacent trunnion or journal of the bar has its supporting engagement is split with projecting ears i^2 , i^2 in conjunction with which a constricting screw i is 15 engaged.

The Fourdrinier machine is operable for the production of a running web of paper of unequal thickness, that is while the web is uniform as to its under surface which is 20 against the wire, it has prominent interspersed upper surface portions with relatively intermediate depressions as represented, for instance, in the sectional view, Fig. 5. A practical manner of adapting the 25 Fourdrinier machine for the production of a web having relatively thick prominent, and low and depressed portions is to employ a plain dandy roll and to render inactive the first suction box L which is to the rear of 30 the dandy roll. The pulp having come along toward and near to the dandy roll is still in such liquid state that the web has been but very slightly or imperfectly formed, and especially by reason of the absence of suction 35 action at the location of the first suction box L. Such pulp in coming against the rotative dandy roll becomes somewhat banked up at the rear thereof as in a manner indicated by x in Fig. 1. The free fibers of 40 the stuff more or less in suspension in the water at the zone of the banking up or ripple x are not of uniform consistency in the semi-liquid or embryo web, but are, as appreciable in paper manufacture, more or less 45 bunched with more watery portions of the incipient web between; and, therefore, in the passage of the paper making stock having the components thereof disposed as just 50 stated, there will be more of a crushing action between the dandy roll and the wire at some places than at others; and the web thence proceeding forward of the dandy roll to and between the couch rolls is one having 55 the surface inequalities to be taken advantage of in the carrying out of the present improved manufacture of paper. The color sprayed onto the felt jacket of the couch roll is carried around by the latter and not only transferred onto the uneven 60 upper surface of the web, but such portions 65

of the color as are on the prominent or high places of the web are, under the rolling pressure action exerted by and between the couch rolls, displaced or "squeeged" from such high places to places of occupancy within the already surfaced depressions or low places. The paper thus produced is not one of a predetermined design or set figure, but such may be as readily and easily produced, if desired, by proper equipment and adaptation of the paper machine therefor; that is, a dandy roll having a figure or design provided on the surface thereof may be employed instead of a dandy roll the working surface of which is only composed by the wire gauze of uniform texture throughout; and when using a design impressing or watermarking dandy roll the rear suction box L is preferably active, that is the suction pump is in effective connection therewith, as well as the forward suction box L^2 . The web having the depressions corresponding to predetermined design or configuration of the dandy roll receives the color surfacing from the couch roll in substantially the same manner as has been heretofore described, which color is by the pair of couch rolls crowded off or displaced from the prominent to the depressed surface portions of the paper. Notwithstanding the 70 fact that the web on which the color is superficially applied is moist and the web receives as much of the color on its prominent portions as on its depressed portions, or, practically, even more, the forcing of the color 75 under pressure action between companion rolls of the machine for the entire disposition thereof within the depressions is so complete as not to change or modify the body color of the paper which in the finished product is visible at the thicker or high 80 places.

Assuming with reference to Figs. 4 and 7 that the stock or stuff is such or so prepared as to produce a medium brown paper, 85 and it is desired that the same shall have a mottling or design of a highly contrasting darker brown: The color employed in the tank E will be of the darker brown color; and y , y represent the natural or body color 90 showing on the cleaned high places of the paper, while w , w represent the surfacing by the darker brown coloring in the depressions. In many cases the paper is not only one having a mottled surfacing, or 95 having different portions of contrasting aspect, but it is also one having varying degrees of translucency in the relatively thick and thin parts thereof; and in many papers produced in accordance with this invention, notwithstanding that the coloring darker than the body color of the 100 paper is found as a facing for the thinner portions of the paper, the latter portions are of the greater translucency. The 105

color variations for contrasting effects in different papers to be produced hereunder may be carried to infinity, the foregoing example of a paper made with contrasting 5 browns being only one of innumerable effects possible to be obtained. While, as has been herein stated, employment is made of liquid coloring material, the invention is not necessarily limited to the use of such material, 10 as in place of a coloring solution to directly impart a surfacing to portions of the area of the paper in which it is ultimately received, a liquid chemical may be employed in substantially the same manner as that described 15 which while inactive to alter the facing of the paper at its high surface portions is effective by chemical action on the portions of the paper comprised in the depressions thereof to alter the body color to a 20 color, tint or shade different from its normal color (or absence of color). While a Fourdrinier machine would be more generally and extensively employed for the making of the moist pulp web, such web may be, of 25 course, as well produced in a paper machine of other type, as, for instance, a cylinder machine; or it may be otherwise produced and supplied. Inasmuch as this invention contemplates in part the provision 30 in any way of a paper sheet or web having relatively prominent and depressed portions, and means for displacing applied material from the prominent surface portions to and onto the depressed portions for acquiring 35 the characteristic appearance of and for the paper as described, the invention is not necessarily limited to any particular manner of producing the web having inequalities of thickness,—as has already been intimated,— 40 nor is it limited in its broader aspect, to any particular mode of applying the liquid coloring, etc., on the surface of a moist pulp web preparatory to the pressure of the web and color thereon while moist to cause, 45 irregularly, the spreading of the color, nor to the manner of, or means for, effecting the color spreading pressure,—it being understood, primarily, that a paper having surface portions of contrasting color, shade or 50 tint, is produced by providing in addition to the means for advancing a moist web, means for applying liquid coloring matter on the surface of such web, together with pressure means for causing the spreading of 55 the color on the surface of the web, irrespective of the specific form and arrangement of the instrumentalities employed.

Referring to Fig. 9, the color is shown as being delivered from a jet or spray pipe *m* 60 onto a roll *n* which acts as an equalizing roll and as a roll for transferring it onto the couch roll *B*.

In Fig. 10, the couch roll is shown as running against an open front of the tank *E*²,— 65 the periphery of the roll forming the tank

boundary. Here the color is taken by the roll to and for application on the uneven surfaced web.

In Fig. 11, the spraying by the co-operative rotative brush, partly submerged in the 70 color tank and blade *H* instead of being onto a couch roll or other roll is sprayed directly onto the running web; and in Fig. 12 the spraying directly onto the running web is indicated as being by means of a jet pipe. 75 The application of the color on the surface of the moist pulp web or sheet instead of being performed at the rear of the couch rolls may be forward of the couch rolls and in relation to a set of the press rolls, one of 80 which will receive and transfer the color onto the paper while a pair of such rolls will be effective for imparting the pressure.

I claim:—

1. The combination with a Fourdrinier 85 machine comprising a dandy roll, and the couch rolls, and operable for the production of a web of paper having prominent and depressed portions at and within the upper surface thereof, of a tank for containing a 90 liquid color, arranged alongside and adjacent the upper couch roll and having a rotatively driven cylindrical brush, a portion of which is submerged in the liquid color in the tank, and a blade having an impingement 95 against the bristles of the brush, whereby under the revoluble movement of the latter in conjunction with such blade the liquid color is sprayed onto the surface of the upper couch roll. 100

2. The combination in a paper machine adapted and operable for the production of a web of paper having prominent and depressed portions at and within one side thereof, of a roll in conjunction with 105 which the uneven surface of the web runs, a tank for containing liquid color arranged adjacent said roll and having a cylindrical rotatively driven brush to be partially submerged in the tank, a blade 110 adjacent an unsubmerged portion of the brush and adapted to have an impingement against the bristles of the brush whereby, under the revoluble movement of the latter in conjunction with such blade, the color 115 taken up by the brush is sprayed upon the surface of the adjacent roll, and further means for imparting a rolling pressure to the paper.

3. The combination in a paper machine, 120 which is adapted and operable for the production of a web of paper having prominent and depressed portions at and within one side thereof, of a roll in conjunction with which the uneven surface of the web runs, 125 a tank for containing liquid color adjacent said roll and having a rotatively driven cylindrical brush partially submerged therein, a blade adjacent the brush and adapted to impinge against the bristles of the latter and 130

4
operable to cause a spraying of the brush-carried liquid onto the surface of the adjacent roll, means for adjusting the blade whereby the degree of its impingement in relation to the brush may be varied, and further means for imparting rolling pressure to the paper.

4. The combination in a paper machine, which is adapted and operable for the production of a web of paper having prominent and depressed portions at and within one side thereof, of a roll in conjunction with which the uneven surface of the web runs, a tank for containing liquid color adjacent said roll and having a rotatively driven cylindrical brush partially submerged there-

in, a blade adjacent the brush and adapted to impinge against the bristles of the latter and operable to cause a spraying of the brush-carried liquid onto the surface of the adjacent roll, a rocking-support on which the blade is mounted, means for confining said support against rocking movement, and further means for imparting a rolling pressure to the paper.

Signed by me at Springfield, Mass., in presence of two subscribing witnesses.
